US00D626130S

(12) **United States Design Patent**
Tsai

(10) **Patent No.:** **US D626,130 S**
(45) **Date of Patent:** **** Oct. 26, 2010**

(54) **PROTECTIVE CASING OF A PORTABLE
STORAGE DEVICE**

(75) Inventor: **Shih-Huang Tsai, Chung Ho (TW)**

(73) Assignee: **A-Data Technology (Suzhou) Co., Ltd.,**
Suzhou, Jiangsu Province (CN)

(**) Term: **14 Years**

(21) Appl. No.: **29/344,856**

(22) Filed: **Oct. 5, 2009**

(30) **Foreign Application Priority Data**

Jun. 4, 2009 (CN) 2009 3 0037284

(51) **LOC (9) Cl.** **14-02**

(52) **U.S. Cl.** **D14/484.1**

(57) **CLAIM**

The ornamental design for protective casing of a portable storage device, as shown and described.

DESCRIPTION

FIG. 1 is a perspective view of my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken line in FIG. 3 defines the bounds of the claimed design and forms no part thereof.
